UNITED STATES PATENT OFFICE.

NATHANIEL S. MONROE, OF ARCOLA, ILLINOIS.

WASHBOARD.

SPECIFICATION forming part of Letters Patent No. 571,574, dated November 17, 1896.

Application filed January 14, 1895. Serial No. 534,889. (No model.)

To all whom it may concern:

Be it known that I, NATHANIEL S. MONROE, a citizen of the United States, residing at Arcola, in the county of Douglas and State of Illinois, have invented a new and useful Improvement in Washboard-Guards, which improvement is fully set forth in the following specification and accompanying drawings, in which—

10 Figure 1 is a perspective view of a washboard in operative position provided with my improved guard; and Fig. 2, a detail view of a sheet-metal blank, showing the initial form of the guard.

15 My invention relates to improvements in washboards; and its object is to provide a simple, inexpensive, and efficient splashboard or guard, whereby operatives may be shielded in front and on the sides from the 20 splashing suds which are liable to be thrown in all directions during the washing process.

The device will be easily understood by reference to the accompanying drawings, in which A designates a washboard of the usual 25 form.

The guard is preferably made of suitable sheet metal, which is first cut out in the form shown in Fig. 2, comprising the rectangular central portion C and the end wings B and slits 30 a, formed at each corner of said central portion. The rounded ends or wing-sections B are then bent approximately at right angles to the central portion C and the edges of the latter bent outwardly at an angle thereto, forming

ledges a', and the wings pivotally connected with the washboard. The ends of said outwardly-turned edges of the portion C rest upon the sides of the washboard and support the guard. The ledges a' serve as soap-holders.

40 It will be observed that if the guard be applied to a two-sided washboard it may be readily reversed by a half-rotation on the pivot and that its position in relation to the board will be unchanged.

45 It is not necessary that the guard be in combination with the washboard when sold, as the blanks may be bent into the finished form by the operator and applied to any washboard, a large tack or small nail sufficient 50 to properly pivot the device in place.

What I claim as new is—

As an improved article a sheet-metal washboard-guard and soap-holder consisting of the rectangular central portion, the end wings 55 bent at right angles thereto, and formed with pivot-holes, and the edges of said central portions bent outwardly forming ledges, all made integral, substantially as and for the purpose specified.

60 In testimony that I claim the foregoing I have hereunto set my hand, this 4th day of January, 1895, in the presence of witnesses.

NATHANIEL S. MONROE.
